Primary Examiner — Leanne Was-Englehart(74) *Attorney, Agent, or Firm* — Fish & Richardson P.C.(57) **CLAIM**

The ornamental design for a dock for portable power system, as shown and described.

DESCRIPTION

FIG. 1 is a front top perspective view of a dock for a portable power system, showing my new design.

FIG. 2 is another front top perspective view thereof;

FIG. 3 is a back top perspective view thereof;

FIG. 4 is another back top perspective view thereof;

FIG. 5 is another back top perspective view thereof;

FIG. 6 is a front view thereof;

FIG. 7 is another front view thereof;

FIG. 8 is a side view thereof;

FIG. 9 is another side view thereof; and,

FIG. 10 is a top view thereof.

The broken lines in each figure illustrate portions of the dock for portable power system that form no part of the claimed design.
